BARREL RING

Frederick R. Schaefer, Youngstown, and Raymond W. Emery, Warren, Ohio, assignors, by mesne assignments, to Republic Steel Corporation, Cleveland, Ohio, a corporation of New Jersey

Application February 18, 1936, Serial No. 64,520

6 Claims. (Cl. 220—61)

This invention relates to improvements in barrel rings, that is to say rings for clamping and sealing removable heads upon open ended steel barrels or drums. It has reference particularly to a closing and sealing ring such that the strength of the closure is relatively great, that is capable of withstanding unusually heavy shocks such as may be encountered for example when the container falls several feet in inverted diagonal position and strikes an unyielding surface on the chime of the container. The specifications established for steel containers intended for certain purposes call for the ability of the container when filled with stated material to remain tight after being dropped in such inclined inverted position upon a cement floor from a height of a stated number of feet. It is a difficult matter to so construct containers of comparatively large size as to withstand tests of this kind, and the present invention is designed to provide a satisfactory closure for that purpose.

One of the objects of the invention is the provision of a rigid ring contracting and holding means adapted to maintain the ends of the ring in circular alignment under severe shocks of any kind.

Another object of the invention is the provision of a separable pivotal connection between the two parts of the contracting clamp, this pivotal connection insuring an even movement of the two ends of the ring toward each other during the operation of the contracting means.

A further object is the provision of supplemental means for holding the two elements of the contracting clamp in rigid relation after the clamp is drawn into fully closed position, said supplemental means preventing dislocation of the ring ends relatively to each other either vertically or horizontally.

Another object of the invention is the provision of a sealing ring of novel cross section, such that its compressing effect is most rapid at the time that the contraction of the ring is begun, while the rapidity of the compressing effect decreases and the leverage increases as the contracting movement of the ring nears its completion.

Still another object is the provision of a rim for the drum so formed in cross section as to reinforce and strengthen the same, and thereby to increase the capacity of the container to resist shocks of impact taken on the chime of the container.

Other objects and features of novelty will appear as we proceed with the description of that embodiment of the invention which, for the purposes of the present application, we have illustrated in the accompanying drawing, in which

Figure 1 is an elevational view of a fragment of a steel barrel embodying the invention.

Fig. 2 is a plan view of the same.

Fig. 3 is a perspective view on a larger scale of a fragment of the sealing ring viewed from the inner side thereof, and showing the clamp by means of which the ring is contracted, and

Fig. 4 is a vertical sectional view of a barrel taken upon a line corresponding to line 4—4 of Fig. 3.

In the drawing 10 represents an open-ended metallic container, such as a drum or barrel, provided with a rim 11 at its open end. The container is adapted to be closed by a head 12 which is provided with an outer upstanding wall 13 adapted to fit within the side wall of the container, and a peripheral flange 14 adapted to overhang the rim 11 of the container. The flange 14 is preferably rounded somewhat, as shown, in order to better receive and hold an annular gasket 15, formed preferably of soft rubber of tubular cross section.

The rim 11 is of special form, and much stronger than the rims conventionally provided in containers of this character. It is produced by rolling the metal of the side wall, as is commonly done, but the rolling operation in the present instance is carried much further than has been the practice heretofore, so that the rolled metal after striking the exterior wall of the container is deflected upwardly and preferably outwardly, as shown at 16 in Fig. 4, and the extreme edge is caused to engage or substantially engage the outwardly bent portion of the rolled metal at the top of the rim. In this manner a double wall of metal is provided along the inner side of the rim. If arranged as illustrated at 16, furthermore, there results a truss effect which still further strengthens the construction and renders it doubly effective in resisting heavy impacts delivered on the chime of the container.

The closure is of the type wherein the head 12 is drawn down to compress gasket 15 by means of a closing and sealing ring 17 which is generally C-shaped in cross section, the upper part of the ring 17 engaging the flange 14 of the head and the lower part of the ring engaging beneath the rounded rim 11. As will be apparent, the contraction of the ring 17 produces a camming action tending to draw the flange 14 and rim closer together.

In the present case we provide two clamp elements 18 and 19 which are sheet metal stampings formed of metal of approximately the same gauge as the ring 17. The main or body portions of these elements are flat and arranged in the same

plane substantially when the ring is in closed position. They each have upwardly extending curved arms 20 and 21 respectively, which are caused to embrace the ring 17 adjacent the ends thereof, and are secured to the same preferably by spot welds. The two clamp elements 18 and 19 also have flanges 22 and 23 which extend at right angles to the body portions of the elements. The flanges 22 and 23 terminate at their upper ends just below the ring 17 but at their lower ends they come together, where a hinge connection is formed between them permitting pivotal movement about a vertical axis. This connection, which is separable, is conveniently made by forming a socket 24 in one of the flanges and a boss 25 in the other flange. The engaging contours of the boss and socket are preferably semi-circular, so that they can turn upon each other readily.

Through aligned holes in the flanges 22 and 23, rather closely adjacent the ring 17, we insert a bolt 26. A nut 27 is threaded onto the bolt, and when tightened down draws the two clamping elements 18 and 19 toward each other, thereby contracting the ring 17. In order to get the ring 17 over the flange 14 of the container head and the rim 11 of the container, it is of course necessary to either loosen the bolt 26 considerably or take it entirely out of the clamp. When the ring is in place the ends thereof tend to stand out from the rim of the container more or less tangentially for a short distance on either side of the split. When the nut 27 is tightened the boss 25 enters the socket 24, the clamp elements then standing at a slight angle with respect to each other. Thereafter, as the nut 27 is further tightened the clamp elements turn about a vertical axis through the center of boss 25 until the body portions of the two elements come into substantially the same plane, when the ring is fully contracted and hugs the rim of the container closely even at the point of the split in the ring.

Between the bolt 26 and the hinge 24, 25 we provide an interlock between the two clamp elements 18 and 19, which cooperates with the bolt 26 and the hinge to prevent relative movement of the clamp elements transversely as well as in a vertical direction. The hinge 24, 25 tends to prevent relative movement transversely, but it is not sufficient to hold the parts securely in the event of heavy impact on the chime of the container. The interlock may advantageously consist of two heavy gauge metal tongue and groove members 28 and 29, the member 28 being welded or otherwise secured to the clamp element 19, and the member 29 being similarly secured to the clamp element 18. Preferably these two members at their outer ends abut against the flanges 23 and 22 respectively. The tongue on the member 28 tapers, as shown in Fig. 3, and its outer extremity 60 extends beyond the edge of element 18 when the parts are in closed position. The groove of member 29 is tapered upon the same angle as the tongue, and the two extremities of this groove member overlap the clamp element 19. It will be obvious therefore that when the nut 27 is tightened down sufficiently to cause the tongue and groove to make close contact with each other, the clamp elements will be locked against relatively vertical movement, and because of the overlapping of these members upon the inner walls of the elements 18 and 19 all relative movement of the latter elements in a direction at right angles to their common plane will be likewise prevented.

In the lower portions of the flanges 22 and 23 we may provide small holes 30 and 31 through

which a wire 32 may be threaded. The ends of this wire may be joined by a seal 33.

It will be observed that in the form of the invention illustrated the bolt 26 and the interlock members 28 and 29 are largely concealed by the body portions of the clamp elements 18 and 19, and that the clamp as a whole presents a neat appearance. It also stands close to the wall of the container, projecting very little beyond the periphery of the ring 17. Hence it does not interfere with the storage of the containers compactly, and is not subject to damage in the handling or transportation of the same.

While we prefer to locate the clamp as herein illustrated and described, it will be apparent that if desired the clamp may be so attached to the ring as to extend horizontally inward above the head of the container. Other changes within the scope of the appended claims may likewise be employed.

Having thus described our invention, we claim:

1. In a container of the class described, a split closing and sealing ring adapted to be contracted into closing position, a pair of clamping elements attached to the ends of said ring extending away from the ring side by side, said elements standing substantially in the same plane, interlocking members attached to said elements on one side thereof adapted to prevent relative movement of the said elements in their own plane, the interlocking member on each element overlapping the other element, whereby relative movement at right angles to the plane of the elements is also prevented, and means for drawing said clamping elements toward each other.

2. In a container of the class described, a split closing and sealing ring adapted to be contracted into closing position, a pair of clamping elements attached to the ends of said ring extending away from the ring side by side, said elements standing substantially in the same plane, interlocking tongue and groove members attached to said elements on one side thereof, whereby relative movement of the said elements in their own plane is prevented, the interlocking member of each element overlapping and engaging the other element, whereby relative movement at right angles to the plane of the elements is also prevented, and means for drawing said clamping elements toward each other.

3. In a container of the class described, a split closing and sealing ring adapted to be contracted into closing position, a pair of clamping elements attached to the ends of said ring, said clamping elements extending downwardly outside of the container side by side, a separable pivotal connection between the free ends of said clamping elements, said pivotal connection being adapted to permit pivotal movement between the elements around a vertical axis through the ring, and a bolt mounted in said clamping elements adjacent the ring, said bolt being adapted when tightened to draw the ends of the ring together.

4. In a container of the class described, a split closing and sealing ring adapted to be contracted into closing position, a pair of clamping elements attached to the ends of said ring, said clamping elements extending away from the ring parallel to each other and comprising flat portions in substantially the same plane and flanges at right angles to said plane, said flanges at the free ends of the clamping elements extending toward each other, a separable pivotal connection in the flanges of the two elements at the free extremities of the latter, said pivotal connecting being adapt-

ed to permit pivotal movement between the elements around a vertical axis, and means mounted in said flanges adjacent the ring for drawing the ends of the ring together.

- 5 5. In a container of the class described, a split closing and sealing ring adapted to be contracted to closing position, a pair of clamping elements attached to the ends of said ring, said clamping elements extending away from the ring parallel to each other and comprising flat portions in substantially the same plane and flanges at right angles to said plane, said flanges at the free ends of the clamping elements extending toward each other, a separable pivotal connection in the 10 flanges of the two elements at the free extremities of the latter, said pivotal connection being adapted to permit pivotal movement between the elements around a vertical axis, means mounted in said flanges adjacent the ring for drawing the 15 ends of the ring together, and interengaging tongue and groove members carried by the said clamping elements between said last named means and said pivotal connection.
- 15 6. In a container of the class described, a split 20

closing and sealing ring adapted to be contracted to closing position, a pair of clamping elements attached to the ends of said ring, said clamping elements extending away from the ring parallel to each other and comprising flat portions in substantially the same plane and flanges at right angles to said plane, said flanges at the free ends of the clamping elements extending toward each other, a separable pivotal connection in the flanges of the two elements at the free extremities 10 of the latter, said pivotal connection being adapted to permit pivotal movement between the elements around a vertical axis, means mounted in said flanges adjacent the ring for drawing the ends of the ring together, and interengaging 15 tongue and groove members carried by the said clamping elements between said last named means and said pivotal connection, said tongue and groove members being flat and being secured to the flat portions of the clamping elements 20 inwardly of the flanges on the latter.
